SUBMARINE

Thomas P. Higgins, Jr., Northridge, Calif., assignor to
Lockheed Aircraft Corporation, Burbank, Calif.

Filed May 29, 1961, Ser. No. 65,381

Term of patent 14 years

(Cl. D71—1)

FIG. 1

FIG. 2

FIGURE 1 is a top perspective view of a submarine embodying my new design;

FIGURE 2 is a rear elevation thereof;

FIGURE 3 is a side elevation thereof, and

FIGURE 4 is a top plan view thereof.

The characteristic features of my design reside in the exhaust nozzle at the rear in combination with the conning tower as best shown in the drawings.

I claim:

The ornamental design for a submarine, substantially as shown and described.
